UNITED STATES PATENT OFFICE.

FREDRICK RICHARD CHOWEN, OF FORT WILLIAM, ONTARIO, CANADA.

STREET AND STATION INDICATOR.

1,331,980.

Specification of Letters Patent. Patented Feb. 24, 1920.

Application filed May 10, 1919. Serial No. 296,257.

To all whom it may concern:

Be it known that I, FREDRICK RICHARD CHOWEN, a subject of the King of Great Britain, of the city of Fort William, Thunder Bay district, Province of Ontario, Canada, have invented certain new and useful Improvements in Street and Station Indicators, of which the following is a specification.

10 My invention relates to improvements in street and station indicators, and the object of my invention is to provide a device of this class, very simple in construction, and consequently one that will not easily get out 15 of order. Another object of my invention is to provide particular means for regulating the tautness of the belt which carries the names of the streets or stations, and in the following specification I shall describe the 20 invention, and what I claim as new will be pointed out in the claim.

Figure 1 is a side elevation of my contrivance with one of the end members of the box removed, showing the interior mechanism in end elevation. Fig. 2 is a front elevation of my contrivance with the front member of the box removed, showing the interior mechanism in side elevation, and Fig. 3 is a front elevation of portion of the 30 contrivance with the door closed.

In the drawings, like characters of reference refer to the same parts.

The contrivance comprises a suitable box A, in which is positioned two vertically-disposed walls B and C. These walls are spaced apart from the side walls D of the box, and in the said walls B and C are journaled the arbors or spindles of certain of the various rollers, hereinafter referred to. 40 So mounting the arbors or spindles prevents the mechanism from being tampered with from the outside, and this is a very important feature.

This invention has reference to that class 45 of street and station indicator in which an endless belt or apron is mounted, and on which is printed or otherwise imposed the names of the streets or stations. In the invention in question, the belt 2 passes over the roller 3 and underneath the rollers 4 and then up over the rollers 5 and around the rollers 6. The roller 3 is mounted on the arbor or spindle 7 which is mounted in the walls B and C, and the rollers 4 and 5 are mounted on arbors or spindles 8, which spindles or arbors are mounted in the walls

B and C. Associated with the roller 3 in such wise as to turn this roller when properly actuated, is a ratchet-wheel 9, which is shown as secured by pins 10 to one end 60 of the roller 3. Mounted adjacent the said ratchet-wheel and on the arbor 7 is a lever 11, the free end of which is controlled by a flexible coupling 12 which passes out through an aperture 13 in the top of the 65 box A and to any convenient point for actuation by the motorman or conductor. a is a collar on the arbor or spindle 7 to keep the lever 11 from longitudinal displacement on said arbor. 14 is a rivet pivoting the pawl 15 to the lever 11. 16 is a spring suitably coupled to the lever 11 and maintaining the pawl 15 in co-operative relationship with the ratchet-wheel 9. By pulling upward on the lever 11, through 75 the means already described, the roller 3 is turned and consequently the name of a street or station exposed through the opening 17 in the box A, will be changed as desired. It will be observed that the roller 3 80 is of greater diameter than the other rollers, consequently the area of the belt 2 in contact therewith will develop sufficient friction so as to insure shifting of the belt 2.

18 is a stop carried by the wall C to limit 85 the downward movement of the lever 11, and 19 is a coiled spring connecting the lever 11 with the wall C. The object of this spring is to return the lever 11 to 90 normal position after operation. 90

Through atmospheric conditions, the material composing the belt 2 is bound to stretch and shrink, and in order to regulate the tautness of this belt, I mount the arbor or spindle 20 of the roller 6 in adjustable 95 bearings in the form of blocks 21 through each of which extends a guide-rod 22, and a threaded rod 23. A block 21 is positioned adjacent each of the walls B and C. 24 and 25 are blocks secured by any suitable 100 means such as screws 26 to the walls B and C. By means of the pins 27, the ends of the guide-rods 22 are keyed in the blocks 24 and 25. 28 and 29 are collars mounted on the rods 23, and keyed thereto by any 105 suitable means such as pins 30, and one above and the other below the blocks 25, so that the rods 23 will be held against longitudinal movement. The upper end 31 of each rod 23 is preferably reduced, and is without 110 threads and is mounted in the blocks 24 so as to give these rods proper support.

32 is a knurled finger-piece or head, suitably coupled to the lower end of each of the rods 23. 33 is a lock-nut threaded on each of the rods 23, and normally rests 5 against the underside of each of the blocks 21. By turning the heads 32 of each of the rods 23, after shifting the lock-nuts 33 as may be required, the blocks 21 are moved either up or down and consequently the 10 roller 6 will be shifted to regulate the tautness of the belt 2. After such regulation, the lock-nuts 33 are screwed up against underside of the blocks 21.

The walls B and C are preferably cut 15 away as shown at *b*, so as to provide ease of access to the ends 32 of the rods 23.

The side walls D of the box A may be hinged thereto as shown at *c* and provided with suitable fastening means *d*.

20 Although I show manually-operated means for moving the roller 3, in order to shift the belt 2, it will be understood that any suitable means may be used for this purpose.

From the foregoing specification, it will 25 be understood that my contrivance is very simple in construction and quite inexpensive, and will perform all the necessary

functions of the more expensive and complicated contrivances that have been designed for this purpose.

30

Various changes in details of construction may be made without departing from the spirit of the invention.

Claim:

In a tensioning device, in combination 35 suitable supports spaced apart; a pair of spaced blocks fixedly carried by each of the said supports and projecting therebeyond; a guide rod carried by each pair of said fixed blocks; a threaded rod journaled 40 in each pair of said fixed blocks and spaced apart from said guide rods; a block intermediate each pair of said fixed blocks and through the opposite ends of which said guide rods and said threaded rods pass, 45 said threaded rods having threaded engagement each with its respective intermediate block; a roller journaled at each end in said intermediate blocks and adapted to exert pressure against an endless belt passed 50 thereunder, and means whereby said intermediate blocks are held in adjusted position on said guide rods and said threaded rods.

FREDRICK RICHARD CHOWEN.
